UNITED STATES PATENT OFFICE.

LEON JOSEPH CREPLET, OF PARIS, FRANCE.

AUTOMATIC TELEAPPARATUS TO LIMIT AND REGULATE THE SPEED OF REVERSIBLE ENGINES.

1,317,270.

Specification of Letters Patent. Patented Sept. 30, 1919.

Application filed October 30, 1916, Serial No. 128,489. Renewed February 6, 1919. Serial No. 275,455.

To all whom it may concern:

Be it known that I, LÉON JOSEPH CREPLET, a subject of the King of Belgium, residing in Paris, France, have invented certain new and useful Improvements in Automatic Teleapparatus to Limit and Regulate the Speed of Reversible Engines, of which the following is a specification.

This invention relates to variable speed and reversible engines and to direct or remote controlling means therefor of the kind employing an ordinary governor driven by an electric motor the current of which is supplied or controlled by a dynamo driven from the engine to be governed; and the invention has for its object to provide improved means for controlling such engines. The aforesaid type of controlling means is described in the specification of British Letters Patent No. 16,673, A. D. 1913, granted to me.

According to the present invention the engine (turbine) or other machine to be controlled drives a dynamo which is in circuit with a constant voltage dynamo of higher voltage driven from an independent source, the two being inversely connected in the circuit, so that any diminution in speed of the former results in an increased resultant voltage in the circuit, or vice versa; and in the same circuit is introduced an electromotor which responds to such variations of voltage, whereby its speed varies inversely with variations of speed of the engine to be controlled; and this motor drives a centrifugal governor which in turn controls such engine, as by means of its throttle. By means of a variable resistance inserted in the excitation circuit of such motor, the standard of normal speed of the latter, and hence that of the engine under control, may be varied at will.

In the accompanying drawings,—

Figure 1 is a diagram showing a simple typical assemblage of elements, with their circuit connections, for realizing this invention;

Fig. 2 is a diagrammatic elevation showing the application of the invention to a reversible machine such as a hoisting engine, the circuit connections being shown in diagram;

Fig. 3 is a speed diagram;

Fig. 4 is a view illustrating the application of the invention to the control of marine turbines for driving a ship either forward or backward, the mechanical apparatus being shown in elevation and the electrical connections in diagram.

Referring first to Fig. 1, A is the machine, engine or prime mover, the speed of which is to be controlled, for example, a steam turbine; *a* is a shaft of this engine, which may be its power or driving shaft; *d* is a dynamo driven directly or indirectly from the shaft *a*; *e* is a constant voltage dynamo driven from any independent source; *m* is an electromotor which directly or indirectly drives a governor *R*, which latter is the governor controlling the engine A, as, for example, by means of a throttle *P* controlling the flow of steam to such engine. Dynamo *d* is shown excited by a field coil *b* in shunt to dynamo *e*; dynamo *e* is shown as excited by a shunt field coil *f*; motor *m* is shown as excited by a field coil *h* which is connected in shunt through a variable resistance or rheostat *r*, the sliding contact *r'* of which may be moved by means, for example, of a lever *L*. The armatures of *d*, *e* and *m* being connected in series, as shown, let us assume, for example, that the dynamo *e* has a constant voltage *E*, of say 240 volts; that the dynamo *d*, whose excitation is constant for any given setting of the rheostat *r*, furnishes 120 volts when its driving shaft *a* runs at the normal speed; that the direction of the electromotive force *D* of dynamo *d* is opposed to the electromotive force *E* of dynamo *e*, so that the voltage *V* fed at *m* is always the difference *E*—*D*, and hence has a value of 120 volts at the normal speed of the machine A; and that the governor *R* runs at a normal speed of say 240 R. P. M., for which speed the admission of steam corresponds to the work of the machine when the excitation of *h* is a minimum, and *V* is equal to 120 volts (neglecting the variation in speed of the governor from 0 to about five per cent., according as its sleeve is at the top or bottom of its movement.) Under these conditions, so long as the load of the machine A does not vary, its speed and that of *d* is constant; the voltage *V* then remains uniform, as also the speed of *m*, *R* provided the rheostat *r* is not changed. If now, for

example, the load increases, A and d slow down, the voltage D diminishes and voltage V increases by the same amount; m and R speed up and the latter acts in the usual manner to increase the admission of steam. Thus, each time that the machine A runs irregularly the speed of R is affected inversely, and it varies the steam admission to adapt it to the new work required of the machine.

If it is desired to change the normal speed of the machine A, the rheostat r is moved, which varies the excitation of m and hence varies the speed of R; thereby a new standard of speed for A is established.

The governor may be installed to act either as a means for limiting the speed or as a regulator of the speed.

Speed limiter.—In the first case it only operates when the number of revolutions of the engine exceeds a predetermined value and it remains inactive so long as the number of revolutions is below that allowed. This is the case in winding engines, lifts, tram cars, etc.

The speed-limiting apparatus fulfills five functions.

1. When starting, it is required only to act for the purpose of obviating shocks and excessive accelerations;

2. When the speed is constant, to prevent it from exceeding a predetermined value;

3. Starting from a certain position of the load to cause the engine to slacken gradually so as to reach the desired point slowly;

4. If in consequence of inattention or of a wrong movement on the part of the operator the desired point is passed, to stop the engine before any damage is done;

5. To modify the rate of speed according to the circumstances of the work, the nature of the load, etc.

To fulfil the first four conditions the position of the sliding contact of the rheostat is made to correspond with that of the load by means of any suitable mechanical connection, while being at the same time also under control of the control lever. Each time the control lever is displaced the sliding contact moves a distance such that the governor is caused to act effectively on the valve gear of the engine.

This will be made clear by reference to Fig. 2, which shows, as an example, a machine A' which may be a hoisting engine such as are used in mines. The sliding contact r' of the rheostat r is displaced by motion derived from the shaft a under control of lever L, which in this instance may correspond to the ordinary reversing lever of such hoisting engines. From the shaft a is driven, through reducing gearing, a shaft S from which movement is transmitted to the sliding contact r' at such rate that the latter makes nearly one complete turn while the

load or cage of the hoist is making its complete travel.

The governor R, driven as before by a motor m, acts in the same manner as before described on a throttle P controlling the admission of steam to the engine. The governor R also acts on the controlling element F of the brake for the engine or hoisting drum, which element may be any known brake-controlling means. The connection between the governor sleeve and the throttle actuates the latter through a spring t which is compressed after the throttle is closed, so as to permit the governor to apply the brake when its sleeve completes its descent. When the sleeve is at x the governor makes, for example, 245 R. P. M., the throttle is open, and the brake is off; when the governor falls (say) from 245 to 240 R. P. M., the sleeve descends to y and closes the throttle. If the governor continues to slow down, passing (say) from 240 to (say) 235 R. P. M., the sleeve descends to z while compressing the spring t, and lifts the controlling arm of the brake-applying device F, which is thus applied more and more as the governor continues to slow down. It is understood that when the throttle is closed it will permit sufficient leakage of steam to enable the operator to manipulate the machine at all times, but at very slow speed.

The reverse lever L is connected in the usual manner to a shaft C which operates to reverse the valve gear in any known manner. An arm on this shaft carries a roller g, which may occupy one of three positions, viz:—

(1) g¹ when the lever is in the stopping position L⁰;

(2) g² when the lever is thrown fully over to L² for running forward;

(3) g³ when the lever is thrown fully over to L³ for running backward.

The roller g, when displaced to g² or g³, tightens a chain i which connects a pulley or sprocket wheel on the shaft S to a similar wheel on the arbor of the sliding contact r'; so that each time the lever L is displaced to drive the machine forward or backward, this causes a certain displacement of the contact r'. This displacement, when the load is at the bottom of its travel and the lever is thrown to L², causes the contact arm to pass from n³ to n⁴ (the resistance of the machine A preventing the chain from turning around the shaft S), which speeds up the governor and admits steam.

If the lever L were to be thrown in contrary direction to L³, this would bring the roller to g⁴ and displace r' from n⁴ to n⁵, a position which slows down the governor so that its sleeve falls to z, and the brake is applied to prevent the machine from running in the wrong direction. Thus in the case of a hoist, when the cage is at the bot-

tom and the lever is brought to L^3 , the brake is set, preventing the starting in the wrong direction; on the contrary when the cage has reached the top of its course the same movement of L to L^3 moves arm p^1 away from n^5 , which releases the brake and allows the descent.

The resistance introduced in traversing the arc from n^3 to n^4 is so proportioned that the throttle is opened sufficiently to run the engine at a speed which is rapid without being dangerous.

From n^3 to n^2 the sliding contact r' , by reducing the magnetism of motor m , tends to speed up the governor; hence the engine accelerates, this being the period of starting O^* , Fig. 3. From n^2 around to n^1 the sliding contact does not modify the excitation of motor m ; this is the period of normal running at constant speed a , b , Fig. 3. Beyond n^1 the contact gradually increases the excitation and reduces the speed of the governor, which gradually cuts off the steam, and the engine slows down until at n^0 the throttle is closed and the engine stops (in period bC , Fig. 3). If at this moment the engine is not stopped, the governor slows down enough further to apply the brake.

Toward the end of the travel the engineer, according to habit, throws lever L from L^2 to L^0 . If he should forget to do this the contact r' will arrive at n^0 before the end of the travel and will pass beyond this position, thus breaking the circuit through r ; in consequence, the governor will slow down and apply the brake, thus avoiding all danger.

Each time that the engine A' reverses its direction, the electromotive force D of the dynamo d is reversed. This voltage must always be opposed to the voltage E , which is constant; to realize this condition a pole-changing commutator may be introduced, driven by friction from the shaft a . This commutator is introduced between the armature of d and its exterior circuit in such manner that at each reversal of direction it transposes the connections. Such commutators and their mode of control are well known and form no part of the present invention.

The fifth object is attained, as will be seen, by having as much sliding contact resistance available to insert in the exciting circuit of the motor as corresponds to the range of speeds to be realized. Only one resistance is then in operation at a time, the others being cut out.

The maximum speed A^* (Fig. 3) depends upon the variation of magnetization which the sliding contact r produces, that is to say, upon the amount of the resistance which it introduces and suppresses gradually.

Let us assume, for example, that the ma-

chine a (Fig. 1) makes 90 R. P. M. when its dynamo d develops 120 volts. We know then the magnetization of m is reduced by half. If we replace the regulating resistance by another reducing magnetization by one-fourth only, the governor will preserve its 240 R. P. M. for a diminution of voltage V (Fig. 1) by one-fourth, that is to say, to 60 volts, which represents the maximum potential of the dynamo d and consequently a speed $A' B'$ (Fig. 3) of the machine reduced by half.

If there is given to the regulating resistance a value still less, the maximum speed of the machine will be reduced still more.

There will be provided as many regulating resistances for the sliding contact r' as it is desired to have of maximum normal running speeds, but there will never be more than one in service.

The more the magnetization of m , that is to say, the voltage of its field h is varied, the greater will be the maximum speed of the machine A^* (Fig. 3).

A great number of maximum speeds A^* , A'^* , etc., can be attained by varying the voltage of the field of m in the following manner. Upon the regulating resistance controlled by the rheostat r , there is arranged in parallel a second resistance that is modified by a sliding contact s (Fig. 2) operative by hand. For example, if s is at s_0 all resistance is eliminated and no displacement of r will modify the magnetization of m and consequently the machine is forced to stop.

If s is put at s_1 , the displacement of r would produce in the magnetization of m the maximum variation.

On bringing s successively from s_0 to s_1 the machine will take on all maximum speeds from zero to A^* (Fig. 3).

Speed regulator.—When the apparatus is required not merely to limit but also continually to govern the engine, the operator operates the sliding contact directly, and it is then made independent of the engine A . For moving the contact it may be carried by a hand lever L .

Each time the operator displaces this lever the governor acquires a new speed, and consequently by acting on the valve gear of the engine imparts a new speed to the latter.

Before displacing the sliding contact the operator must set the valve gear of the engine in the required direction. The two operations are under control of a single lever L , as has been described with reference to Fig. 2.

When a forward and reverse movement of the drive shaft are obtained by two separate engines (on turbine boats for example) the mechanism opens sometimes the regulating

valve of one engine and sometimes the regulating valve of the other, according to the direction of motion required, as will be described with reference to Fig. 4.

5 This object may well be attained by providing each engine with a governor. The control lever then acts on the excitations of the motors operating the governors in the desired direction.

10 This is illustrated in Fig. 4, where the two engines A^1 A^2 have their admission valves P^1 P^2 operated by governors R^1 R^2 driven respectively by the motors m^1 , m^2 , the fields of which are in series with two rheostats r r^2

15 controlled by sliding contacts r' connected to the control lever L which is movable from the stopping point L^0 to either full ahead at L^4 or full astern at L^5 . When this lever is at the stopping point the contacts occupy

20 the positions shown, the two governors then having their sleeves fully down and their admission valves closed. To run forward L is displaced from L^0 to L^5 , which leaves r' out and cuts in r^2 ; this speeds up m^1 and R^1 ,

25 which latter opens the forward admission valve P^1 , driving the forward engine A^1 while the motor m^2 preserves an invariable speed, because the resistance r does not change. For running backward the con-

30 trary movement is made, which drops R^1 to the minimum and speeds up m^2 R^2 , which opens the admission to the backward running engine A^2 . The governors R^1 R^2 may operate the admission valves P^1 P^2 in any

35 suitable manner, as through the intervention of auxiliary oil motors, the valves to which are controlled by the governors, as is well known and in common use on electro-generating turbines of constant speed. The main

40 circuit has at E a uniform voltage generated by a dynamo (as e , Fig. 1), and is in series with the dynamo d which is driven from the propeller shaft a , the electrical arrangement being thus the same in this respect as shown

45 in Fig. 1. The pilot's control apparatus Q is shown as similar to the existing marine telegraph. The lever L carries the sliding contact r' which always makes contact with an arc u connected to one circuit lead, and

50 in its mid-position L^0 makes direct connection through sliding contacts with the wires leading to the respective exciting coils of the motors m^1 m^2 . On displacing the lever in one direction toward L^4 it introduces the re-

55 sistance r^2 in series with the exciter of m^1 ; on displacing it in the contrary direction toward L^5 it introduces the resistance r in series with the exciter of m^2 . By means of a reversing commutator as referred to here-

60 in above, the electromotive force D generated by d is always opposed to the exterior voltage E .

It results from these arrangements that we have in the motors m^1 m^2 :

65 240 volts when the screw is at rest;

240—120=120 volts when the screw is at full speed forward or backward.

The governors are so adjusted that the sleeve of each is at its bottom stroke with the admission valve closed, as for example, 70 240 R. P. M.; or at its top stroke with the admission valve open at 250 R. P. M.

The resistances r r^2 are so proportioned that when the screw is at rest, that is, when the voltage at the motors m^1 m^2 is at 240 75 volts, the governors make 240 R. P. M. for R^1 and 240 R. P. M. for R^2 if the handle is at L^0 ; 500 R. P. M. for R^1 and 240 R. P. M. for R^2 if the handle is at L^4 ; 240 R. P. M. for R^1 and 500 R. P. M. for R^2 if 80 the handle is at L^5 .

Hence, if the handle is thrown from L^0 to L^4 , R^1 accelerates and opens the admission valve P^1 , and the screw is driven (say) forward; R^2 slows down as the potential at 85 the motors gradually diminishes. At full speed it falls to 120 volts, which gives for the governors:

$$\frac{500 \times 120}{240} = 250 \text{ R. P. M. for } R^1 \quad 90$$

$$\frac{240 \times 120}{240} = 120 \text{ R. P. M. for } R^2$$

Consequently, the admission valve P^1 for 95 engine A^1 is wide open and valve P^2 remains closed. If the screw tends to race, as on lifting out of water, R^1 slows down, shutting off the steam and reducing the speed to the normal.

It will be understood that for each intermediate position of the handle L the screw will take a speed proportional to the angle of displacement of L . When reversing the control handle L , the conditions are reversed and the screw is driven in the contrary direction. 100 105

If the screw is at full speed and it is desired to reverse the speed very quickly, it is only necessary to throw the handle L over from one extreme position to the other. If from L^4 to L^5 the excitation of motor m^1 is increased by (say) 4%, m^1 slows down to 240 R. M. P. and all steam is cut off from the turbine A^1 . If the pilot thus reverses the lever instantly, that is, before the screw has time to slow down, the governors at the end of this movement will have 120 volts at their motors; their speeds will therefore be half of that given above when the screw is at 110 115 120 rest and the lever at L^5 , namely:

$$\frac{240}{2} = 120 \text{ R. P. M. for } R^1 \text{ and}$$

$$\frac{500}{2} = 250 \text{ R. P. M. for } R^2, \quad 125$$

which shows that the governor for engine A^2 is open, admitting counter-steam. Under the effect of this steam the screw slows down rapidly, thus causing the voltage at the mo- 130

tors to ascend, until upon stopping it reaches 240 volts. We have then: 240 R. P. M. at the governor R^1 and 500 R. P. M. at the governor R^2 .

5. The turbine A^2 receives full admission and proceeds to drive the screw; the voltage diminishes at the motors as the speed rises, until R^1 attains 120 R. P. M. whereupon equilibrium is again established.
10. It has been stated that the excitation of the dynamo operated by the engine to be controlled is constant. It follows consequently that the voltage it delivers is proportional to its number of revolutions. A voltmeter 15 shunted across its terminals will indicate or register at any distance the speed of the engine at every instant.

In order that the governor may control the machine or engine to which it is attached 20 according to a specified rule of working, it is not always sufficient that it should act on the driving force. In a case where the kinetic energy accumulated in the engine would prevent it from slowing down, or 25 where the engine continues to move in spite of the elimination of the driving force (as in the case of a hoist when the load is descending), it is necessary for the governor to create a resisting effort. It may apply either 30 to the brake, or the counter-pressure steam (*i. e.* the steam used for reversing an engine) or a counter-current in an electric motor.

What I claim and desire to secure by Letters Patent of the United States is:—

35. 1. Means for controlling the speed of a machine comprising a governor, an electric motor continuously driving such governor, a circuit feeding said motor including a source of constant voltage and a dynamo 40 driven by the machine to be governed, generating a lesser variable voltage with its potential opposed to that from said source, whereby the speed of the motor varies inversely to that of the dynamo.

45. 2. Means for controlling the speed of a machine comprising a governor, an electric motor continuously driving such governor, a circuit feeding said motor including a source of constant voltage and a dynamo 50 driven by the machine to be governed, generating a lesser variable voltage with its potential opposed to that from said source, and a variable rheostat for controlling the excitation of said motor.

55. 3. Means for controlling the speed of a machine comprising a governor, an electric motor continuously driving such governor, a circuit feeding said motor including a source of constant voltage and a dynamo 60 driven by the machine to be governed, and a plurality of variable rheostats for controlling the excitation of said motor, having independent means for operating them.

4. Means for controlling the speed of a

machine comprising a governor therefor, an 65 electric motor continuously driving the governor, a circuit feeding such motor, a dynamo in said circuit driven by said machine, and means independent of said circuit for varying the excitation of said motor. 70

5. Means for automatically controlling a reversible machine comprising a governor and a control gear including a reversing lever, an electric motor continuously driving said governor, a circuit feeding such motor, 75 and means independent of such circuit for varying the excitation of said motor, comprising a rheostat operated by said reversing gear.

6. Means for controlling the speed of a 80 machine, comprising a centrifugal governor controlling such machine, an electric motor driving such governor, a circuit feeding such motor, including a source of constant voltage, and a dynamo driven by the machine to be governed, and means controllable independently of said circuit for varying the excitation of said motor. 85

7. Means for controlling the speed of a 90 machine, comprising a centrifugal governor, an electric motor driving such governor, a circuit feeding such motor, such circuit having a source of constant voltage, a dynamo of constant excitation driven by the machine to be governed, connected in said circuit, 95 with its electromotive force opposed to and less than the voltage from said source, whereby the speed of the governor motor augments as that of said dynamo diminishes, and vice versa, so as to actuate the governor in the direction required for the regulation of the machine.

8. The system of claim 7 combined with means for varying the standard speed, comprising a resistance introduced in the inductor circuit of the governor motor, with manually controlled means for varying such resistance. 105

9. The system of claim 7 combined with means for reversing the direction of rotation of such machine. 110

10. The system of claim 7 combined with means for reversing the machine, operated manually, and speed-controlling means operated automatically from the machine to be governed. 115

11. The system of claim 10, including a rheostat for changing the resistance in the inductor circuit of the governor motor, operated from both the reversing means and the machine. 120

12. The system of claim 10, comprising a rheostat for changing the resistance in the inductor circuit of the governor motor, and means for operating it from both the reversing means and the machine, such means comprising a connection for shifting the rheostat geared to the machine to be governed, 125

and a connection to the reversing means adapted to displace the rheostat to vary the speed of the governor motor and hence to control the speed of the machine in either

5 direction.

In witness whereof, I have hereunto

signed my name in the presence of two subscribing witnesses.
